US0D1052340S

(12) **United States Design Patent** (10) **Patent No.:** **US D1,052,340 S**
(45) **Date of Patent:** **** Nov. 26, 2024**

(54) **CONTAINER FOR A MICRO PUREE MACHINE**

(71) Applicant: **SharkNinja Operating LLC**, Needham, MA (US)

(72) Inventor: **Eric Holzer**, Needham, MA (US)

(73) Assignee: **SharkNinja Operating LLC**, Needham, MA (US)

(**) Term: **15 Years**

(21) Appl. No.: **29/837,885**

(22) Filed: **May 9, 2022**

(51) LOC (14) Cl. **31-00**

(52) U.S. Cl. **USPC D7/413**

(58) **Field of Classification Search**

(57) **CLAIM**

The ornamental design for a container for a micro puree machine, as shown and described.

DESCRIPTION

FIG. 1 is a top, front, right side perspective view of a container for a micro puree machine, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front and right side perspective view thereof; and,

FIG. 9 is a bottom, rear and left side perspective view thereof.

The broken lines in the drawings depict portions of the container that form no part of the claimed design.

1 Claim, 6 Drawing Sheets
